UNITED STATES PATENT OFFICE.

FRANK C. CARROLL, OF PAINESVILLE, AND THOMAS FLEMING, OF CLEVELAND, OHIO.

RAILWAY-SWITCH.

No. 832,840.

Specification of Letters Patent.

Patented Oct. 9, 1906.

Application filed December 16, 1905. Serial No. 291,991.

To all whom it may concern:

Be it known that we, FRANK C. CARROLL, residing at Painesville, in the county of Lake, and THOMAS FLEMING, residing at Cleveland, 5 in the county of Cuyahoga, State of Ohio, citizens of the United States, have invented a certain new and useful Improvement in Railway-Switches, of which the following is a full, clear, and exact description, reference being 10 had to the accompanying drawings.

This invention is an improvement upon the railway-switch mechanism which forms the subject-matter of our prior patent, No. 778,008, granted December 20, 1904; and the 15 invention consists in the novel combination of parts shown in the drawings and hereinafter described, and pointed out definitely in the claims.

In the drawings, Figure 1 is a plan view of 20 the mechanism when the switch is arranged for the passage of a train from the main to the side track. Fig. 2 is a plan view of the mechanism in the position which it automatically assumes after a train has passed onto 25 the side track and has traveled along said side track far enough to clear any train passing on the main track; and Fig. 3 is a transverse sectional elevation from the right side of Fig. 2.

30 Referring to the parts by letters, A A' represent the two rails of the main track.

B B' represent the two rails of the side track.

E represents a bar or rail which lies just 35 inside and normally in substantial contact with the side-track rail B, and it extends from the point at which the side-track rail B diverges from the main-track rail A a sufficient distance to enable it to act in the manner to be described.

The part a of the main-track rail A between the crossing D and the switch-point C is movable transversely, and its front end is joined to the front end of the bar E to form 45 said switch-point C. The part b of the side-track rail B' between the crossing D and the switch-point C' is also movable, and said rail-sections a and b and said bar E are all rigidly connected substantially as shown so as to 50 move in unison.

By the side of the main track and parallel thereto is a rock-shaft G, having a plurality of depending arms g, which arms are connected by suitable links, &c., with that movable

structure composed of the track-sections a 55 and b and the bar E. The two switch-points C C' rest upon and are secured to a transversely-movable bar H, which passes under the track-rails A' B', whereby said points are held down in the plane of said rails. This 60 bar is connected, by means of a link h, with one of the arms g on said rock-shaft, which arm is also connected by a link j' with the crank-arm j on the bottom of the vertical standard J of the switch-stand K. Another 65 bar H' passes under the rails A' and B' and also under the bar E and the rail-sections a and b, which are secured to the bar H', whereby this part of said rail-sections and bar E are also held down. A link M, connected 70 with another one of the arms g of the rock-shaft G, is connected with a plate e, secured to the under side of the bar E, which plate extends under the side-track rail B'. Another plate e' is secured to the under side of 75 said bar E and extends beneath said side-track rail B', and this plate is connected by a link N with another arm g on said rock-shaft G.

The ends of the two rail-sections a and b extend on opposite sides of the frog-point D 80 and diverge in the usual way. These rail-sections are, however, rigidly fastened together adjacent to said frog-point by a bolt-rod P, whose extension is pivotally connected with a lever R. This lever is pivoted 85 upon a fixed pivot-pin r and is movable in a horizontal plane only. The other end of said lever is pivotally connected with the link N.

The switch-stand post J is provided with 90 the usual operating-lever T, which is adapted to be swung on a horizontal pivot t into a horizontal position above a horizontal plate k on the switch-stand or to swing down automatically into a vertical position when said 95 arm comes above the notch k' in said plate. A spring-latch U may be provided for automatically engaging with said arm to hold it down. When now it is desired to throw the switch to permit a train to pass onto the side 100 track, this lever T is unlocked and is raised out of said notch k' and the switch-stand post is turned. This rocks the rock-shaft G, which, through the instrumentalities described, causes a movement toward said 105 rock-shaft of switch-point end of the structure composed of the rail-sections a and b and the bar E and a movement in the contrary

direction of the end of said structure adjacent to the crossing D. When the rock-shaft moves in the direction referred to, it raises one or more weighted arms g^3 , secured thereto. 5 A train going from the right of Fig. 1 will now be guided onto the side track. In so doing the flanges of the car-wheels pass between the bar E and the side-track rail B', and thereafter so long as any wheel-flange lies 10 between said rail and bar E it will hold the bar E away from said rail B' and will therefore hold the switch open. The bar E is of such length that some wheel-flange is always between the bar E and rail B' so long as the 15 train is passing onto the side track and until it has gone far enough to enable a train on the main track to clear it. Therefore when the first wheel-flange of a train goes between said bar E and rail B' the man who opened 20 the switch may leave it and go about his business. When the train has passed entirely onto the side track and beyond the bar E, the weights g^3 will turn the rock-shaft G, and it will move the switch structure to the 25 position shown in Fig. 1, thereby putting the track in condition for a train to pass along the main track. When the switch structure moves to this position, the switch-stand post J will be simultaneously turned until the 30 lever T thereon is brought above the notch k' in the disk k , whereupon said lever will swing down into said notch and be locked therein, and thereby prevent the accidental opening 35 of the switch. It will be noticed that simultaneously with the opening of the switch there will be a movement of the rails a b at the crossing D, a movement produced through lever P and link N, which will put the crossing into proper position to guide the wheels 40 in the track-section a or b onto the main-track rails A or B as required.

Having thus described our invention, we claim—

1. The combination of a railway-switch, 45 its operating mechanism and mechanism which closes said switch when permitted so to act, with a long movable bar normally lying close to the inner face of one of the side-track rails and rigidly connected with the switch-point associated with said rail, and mechanism connecting said bar with the switch-closing mechanism.

2. The combination of a railway-switch, a switch-stand, and connections between the 55 switch-points and switch-stand mechanism, a rock-shaft mounted adjacent to and outside of a main-track rail, a long movable bar which normally lies close to the inner face of one of the side-track rails, mechanism connecting said rock-shaft with the switch-stand mechanism and with said movable bar, and weighted arms secured to said rock-shaft and adapted to turn the same in the direction 60 which closes the switch and moves said bar 65 toward said side-track rail.

3. The combination of a railway-switch, its operating mechanism, and mechanism by which the switch is automatically closed when permitted to so move, with a long bar which normally lies close to the inner face of the outer side-track rail, a transversely-movable bar whose ends extend beneath the outer side-track rail and the outer main-track rail, which bar passes also beneath the movable switch members and said movable bar and is 70 secured to them, and mechanism connecting said bar with the switch-closing mechanism.

4. The combination in a railway-switch, of the main-track rails A, A', the side-track rails B, B' and the rail-sections a , b , with a movable 80 bar E which normally lies close to the inner face of the side-track rail B', means rigidly connecting said bar and rail-sections a , b , switch-operating mechanism and connections between the switch-operating mechanism 85 and the structure composed of said rail-sections a , b , and bar E, and the devices connected with them.

5. The combination in a railway-switch of the main rails A, A', the side-track rails B, B', 90 and the rail-sections a , b , whose front ends carry the switch-points, with a movable bar E which normally lies close to the inner side of the outer side-track rail B' and is rigidly connected at its front end with the adjacent 95 main-track rail-section a close to the switch-point at the front end thereof, a bar H secured to the under side of the connected front ends of said rail-sections a and bar E, which bar passes under the rails A' and B', a 100 switch-stand, its operating mechanism, and connections between said mechanism and the bar H, a rock-shaft mounted in bearings outside of the main-track rail A', weighted arms secured to said rock-shaft, other arms 105 which are respectively secured one to the said switch-operating mechanism, and all of the others with the movable bar E.

6. The combination in a railway-switch of the main rails A, A', the side-track rails B, B', the rail-sections a , b , whose front ends carry the switch-points, with a movable bar E which normally lies close to the inner side of the outer side-track rail B' and is rigidly connected at its front end with the adjacent 115 main-track rail-section a close to the switch-point at the front end thereof, bars H, H' secured to the under sides of said rail-sections, a and b and bar E, which bars pass under the rails A' and B', a switch-stand, its operating 120 mechanism and connections between said mechanism and the bar H, a rock-shaft mounted in bearings outside of the main-track rail A', weighted arms secured to said rock-shaft, other arms which are respectively 125 secured one to the switch-operating mechanism and all of the others to the movable bar E, the rails B and A meeting in a frog-point, and the rear end of the rail-sections a , b extending on the opposite side of said frog- 130

point, means connecting said rail-sections *a*, *b*, in front of the frog-point, a rocking lever pivoted on a vertical pivot adjacent to the frog-point and connected with said rail-sections *a* and *b* in front of said frog-point, there being also a connection between said lever and one of the devices connecting the bar *E* with a rock-shaft arm.

In testimony whereof we hereunto affix our signatures in the presence of two witnesses.
